AUTOMATIC PROTECTOR AGAINST OVER-
HEATING AND LACK OF OIL OR OIL PRES-
SURE

Roy W. Jones, Hialeah, Fla.

Application July 11, 1938, Serial No. 218,665

5 Claims. (Cl. 123—146.5)

This invention relates to automatic protective means for internal combustion engines and it has more particularly to do with a special provision for stopping operation of an automotive 5 gasoline engine or other internal combustion motor similarly equipped, in case of overheating or dangerous loss of oil or oil pressure, whereby to prevent damage to the engine.

The prime object of the invention is to produce a simple yet practical and efficient electrically operated system which is readily installed in connection with the engine operating and controlling equipment on an automobile or in connection with any other engine installation 15 without material alteration in the regular operating and controlling equipment and to attain other particular objects and advantages as will hereinafter more fully appear.

The invention consists in the novel general arrangement of the system and in the particular elements or parts thereof as hereinafter described and defined in the appended claims, reference being had to the accompanying drawing, the sole figure of which is a diagram illustrating a complete arrangement and adaptation of the system 25 of the present invention.

With reference to the accompanying drawing, it is first noted that the illustration is more particularly of an adaptation of the invention in an installation upon an automobile or other motor vehicle, a fragmentary portion of the engine block being shown and designated generally by the numeral 1. Shown more or less conventionally with the engine block is the usual manifold 2 through which the fuel is drawn into the engine during operation from the carburetor 3. Other than the three parts just enumerated, no further illustration of the engine and directly associated parts are illustrated. Suffice it to say that the engine may be of any internal combustion type whereby suction is created in the fuel intake manifold during the operation of the engine, as this enters into the present invention as will later more fully appear, and that the ignition system 35 includes the usual ignition coil (not shown) and an electrical circuit which is of the usual general character and including a manually operable switch which may be utilized in the regular way and also in special correlation with certain of the elements included in the system of the present invention.

As shown in the diagram, the ignition switch, designated by the numeral 4, is provided with a circuit breaking element (not shown) which is operated by a rotatable element indicated conven-

tionally, as at 5, said element 5 being provided with a suitable opening 6 for the reception of a key by which it may be rotated manually in the usual manner.

As thus far described, the switch 4 controls the ignition circuit in the regular way and it is here noted that the switch is connected at one side to a wire 7 leading through an ammeter 8 to one pole of which is grounded, as at 10. From the opposite side of the switch 4, a wire 11 leads 10 to the usual ignition coil (not shown) which latter is obviously connected to the usual distributor for the respective spark plugs, it being, of course, understood that the circuit is grounded in the usual manner beyond the spark 15 plugs.

In one practical adaptation of the present invention, provision is made for directly operating the rotatable element 5 of the ignition switch 4 to break the circuit through the wires 7 and 11 20 to automatically stop operation of the engine upon an undue increase in temperature or dangerous decrease in the supply or pressure of the lubricating oil as will now be set forth with particularity. As shown, the rotatable element 5 of the switch 25 4 has one end portion of a connecting rod 12 pivotally attached thereto with crank-like effect at one side of its axis, as at 13, the opposite end of said rod 12 being pivotally attached to a rocking lever 14, which latter is operably connected, 30 as at 15, to a solenoid bar 16 working in the coil 17. Normally, with the coil 17 deenergized, the rotatable switch element 5 is free to be actuated by application of the key in the slot 6 provided therefor to either open or close the switch, at 35 will, the solenoid bar 16 being accordingly moved inward or outward in the coil 17, as the case may be, by the lever and rod connection with the element 5. In this connection, it is noted that for the purpose of illustration the element 5 of 40 the switch is rotated clockwise to close the ignition circuit and counter-clockwise to break the circuit. Hence, when the solenoid coil 17 is energized and the bar 16 thereby retracted, the connection of the rod 12 with the element 5 is such 45 that the latter is rotated in the direction to break the circuit.

As the energization of the solenoid coil 17 is governed by the relative temperature of the engine and also by the quantity of the lubricating oil supply, a heat indicator 18 and an oil indicator 19 are provided, said indicators being conventionally shown in the drawing, and, in practice, being preferably located on the instrument board of the vehicle in sight of the driver. The in- 55

dicator 18 is provided with a movable pointer 20 and the indicator 19 with a similar pointer 21, said pointers being each connected to a circuit wire 22, which is grounded, as at 23.

- 5 In the illustration, the heat indicator 18 is provided with an arcuate scale 24 on its dial with which the pointer 20 cooperates, an electrical terminal stop 25 being provided adjacent the graduation of the scale 24 designating a maximum degree of temperature and against which the pointer moves into contact when the temperature of the water in the circulating system or part of the engine with which the indicator has a thermal connection reaches that particular maximum, while the pointer 21 of the oil gauge 19 cooperates in a similar manner with the arcuate scale 26 on the dial of the latter indicator and moves into contact with an electrical terminal stop 27 which is correlated to the graduation on 10 the scale 26 which is indicative of a minimum degree of oil pressure or a minimum level of the oil supply, as the case may be. The respective stop terminals 25 and 27 are connected, as at 28' and 27', to a circuit wire 28 which is in 15 turn connected to one end of the solenoid coil 17, as at 29. The circuit in which the solenoid coil 17 is located is completed by a wire 30 which leads from the opposite end of the coil to a stationary terminal contact 31 with which a movable contact 32 is engaged and disengaged as will 20 be presently described. The said movable contact 32 is connected by a wire 33 to the ammeter 8 which latter, as hereinbefore described in connection with the ignition circuit, is connected to one pole of the battery 9, the opposite 25 pole of which is grounded, as at 10.

Normally, when the engine 1 is not operating, the movable contact 32 is out of engagement with the stationary contact 31 and the circuit for the 30 solenoid coil 17 is therefore broken. However, as will be presently more fully described, the movable contact 32 is moved into engagement with the stationary contact 31, thereby closing that 35 part of the circuit between the solenoid coil 17 and the battery or source of electrical energy 8.

At this time the portion of the solenoid circuit between the coil 17 and the ground 23 through the respective indicators 18 and 19 may or may 40 not be broken, depending upon the degree of temperature or the oil supply or its pressure. Normally, with the oil supply or pressure above a predetermined minimum and the temperature below a safe maximum, the pointers 20 and 21 of the indicators 18 and 19 are off the respective 45 circuit terminal contacts 25 and 27 and the solenoid circuit is obviously broken, at which time the ignition switch 4 may be set manually by application of the regular key to close the ignition circuit and the engine placed in operation by actuating the starter (not shown) in the regular 50 way.

The engine will thus continue to operate until deliberately stopped by the driver by opening the 55 switch 4 manually or by other means under his control in the usual way or the switch 4 may be automatically actuated to break the ignition circuit by reason of the hereinabove described cooperative connection between the switch element 5 and solenoid bar 16 should oil or heat trouble develop and cause the solenoid circuit to be closed by the engagement of the pointer of either indicator 18 or 19 with the circuit terminal contact thereof.

70 An essential feature of the present invention

is the provision of means operatively connected and controlled by and with the operation of the engine for automatically moving the movable circuit contact 32 into and out of engagement with the stationary contact 31. For this purpose the movable contact 32 is operated by a vacuum device connected with the intake manifold 2 of the engine so that, by the suction created in the manifold during the operation of the engine, said vacuum device operates to hold the contact 32 in engagement with the contact 31 to effectively connect the circuit wires 30 and 33, provision being preferably made for a delayed operation of the vacuum device for a period of a few seconds after starting operation of the engine and until a definite oil pressure is built up in the lubricating system for the engine before engagement of the contacts 31 and 32 is effected and at the same time said vacuum device operates quickly to release the contact 32 from the contact 31 when operation of the engine is stopped. As shown more or less conventionally in the drawing, the vacuum device comprises a hollow cylindrical body 34 which is connected by a hollow nipple extension 35 communicably with the fuel intake manifold 2. The hollow body 34 affords a vacuum chamber which is closed by a diaphragm 36 which may have sufficient inherent resiliency and set to normally urge its central portion outwardly, or, as shown, a supplemental spring element 37 may be provided between the diaphragm and the opposed wall of the body 34 to urge the diaphragm outwardly. Projecting axially from the diaphragm 36 is a plunger stem 38 which is pivotally attached, as at 39, to a rock-lever 40, which latter is pivotally mounted at one end, as at 41, and carries at its opposite end said movable contact 32 which is suitably insulated therefrom.

Normally, when the engine is not operating, the outwardly urged diaphragm 36, through the connection 38 with the rock-lever 40, holds the movable contact 32 away from the stationary contact 31, but after the engine is in operation the vacuum created in the chamber of the device 34, due to the suction in the fuel intake manifold 2, causes the diaphragm to move inwardly under the external atmospheric pressure and the engagement of the movable contact 32 with the stationary contact 31 is thereby effected, which engagement is held as long as the vacuum is maintained in the body 34.

In order to provide for a delayed engagement of the movable contact 32 with the stationary contact 31, the plunger stem 38 is provided with an axial bore 42 in its inner end portion which opens normally into the vacuum chamber of the body 34, said axial bore 42 having a restricted lateral port 43 open to the atmosphere outside of the diaphragm 36. Mounted on a supporting yoke 44 within the vacuum chamber of the body 34 is a valve head 45 which is opposed axially and in normally spaced relation to the inner end of the axial bore 42 of the plunger stem 38, by which provision a limited quantity of the outside air is drawn into the vacuum chamber until the suction in the fuel intake manifold increases after the engine has started to operate sufficiently to build up a partial vacuum in the chamber of the body 34 so that the diaphragm 36 moves inwardly but with delay, the inward movement of the diaphragm continuing until the inner end portion of the plunger stem is arrested by its engagement with the valve head 45, whereupon further inward movement is prevented and the communication with the outside

air is cut off and sufficient vacuum is maintained in the chamber to hold the contact 32 in engagement with the contact 31. It is, of course, understood that the area of the restricted port 43 is predetermined for the effect of the delayed operation of the movable contact 32, as and for the purpose described, and that there is ample provision obviously made to assure the proper electrical engagement of the contact 32 with the contact 31 and at the same time afford an effective closing of the passageway through the bore 42 when the inner end of the plunger stem 38 is arrested in its inward movement by engagement with the valve head 45.

15 Instead of providing for the automatic operation of the ignition switch by means of the solenoid in the heat and oil indicator circuit and including the respective connecting elements between the solenoid bar 16 and the rotatable switch element 5, as shown in the accompanying drawing, that particular type of switch and automatic operating elements may be eliminated and in place of the switch 4 another conventional type of ignition switch may be substituted, said 20 substitute switch being obviously opened and closed solely by manual manipulation, while in place of the solenoid and operating connections as with the switch 4, a simple circuit breaker or relay switch may be provided directly in the 25 ignition circuit. That is to say, it is, obviously, only necessary to incorporate in the ignition circuit a normally closed relay type switch the electromagnet of which is substituted in the system in place of the solenoid coil 17 and connecting 30 it between the wire 28 and the stationary circuit breaker terminal 31 by the wires 29 and 30.

With this modification the system of the present invention operates with the same effect as installations where the type of switch element 4 is employed and operated by the solenoid. In this connection it may be here also noted that the circuit breaking and controlling means may be further modified within the spirit of the invention as defined in the appended claims.

45 From the foregoing it is noted that an automatic protective system is provided which is readily applied in connection with the installation of automotive internal combustion engines or engines similarly equipped and installed for other uses so as to automatically stop operation 50 of the engine in case of overheating or loss of oil or oil pressure and thereby prevent damage to the engine which might otherwise occur due to the neglect of the driver to observe and respond to instrumental indications of the 55 contingency. By the present invention, not only is stopping of the engine accomplished automatically but the heat and oil indicators may be also conveniently located on the instrument board in view of the driver so that he may observe the 60 indications of rise of temperature and loss of oil or oil pressure and that in the event the driver fails to note the indication before the engine stops operating, he may, upon cessation 65 of operation note the cause from the reading on the indicator or indicators and not attempt to start the engine again until the trouble has been rectified. There is a particular advantage in the 70 practical application of the system of the present invention, particularly in the installation of the same on an automobile or the like, in that the stopping of operation of the engine is automatic whether the combined mechanically and manually operable ignition switch is utilized or a solely manually operable ignition

switch and separate circuit breaker are provided in the ignition circuit, particularly as the engine will not ordinarily start again automatically but has to be started by means of the regular starting device, and should the driver again start the 5 engine without observing the indicators on the instrument board or heeding the warning by the stoppage of operation, the restarted engine will operate for only a few moments and again stop automatically through the same instrumentality which first caused it to stop. There is a still further advantage in providing the circuit terminal elements 31 and 32, one of which is movable with respect to the other and automatically controlled by the operation of the 10 engine and provided with means for delaying the closing of the circuit by the engagement of the movable contact with the stationary contact so that sufficient oil pressure is produced in the lubricating system to lift the pointer 24 off the 15 circuit terminal stop 27 before the circuit for the solenoid coil 17 or the magnet of an equivalent switch, as the case may be, can be closed to effect the breaking of the ignition circuit, by which provision automatic stopping of operation 20 of the engine does not occur unless the temperature is raised or the oil supply is lost or reduced 25 in pressure during operation of the engine.

What is claimed is:

1. In a protective system for operating internal combustion engines, a regular ignition circuit including a manually operable switch for opening and closing the circuit, at will, electrically operated supplemental means for breaking the ignition circuit, said supplemental circuit breaking means having a separate operating circuit and a circuit breaker in its circuit normally open when the engine is not operating but being automatically closed with relayed action by the effect of the operation of the engine, a 30 temperature and/or lubricant indicator or indicators for the engine, and normally open circuit closing means on said indicator or indicators 35 for automatically closing the operating circuit of the supplemental circuit breaking means for the ignition circuit upon the occurrence of an abnormal condition in the engine translated through said indicator or indicators.

2. In a protective system for operating internal combustion engines, a regular ignition circuit including a manually operable switch for opening and closing the circuit, at will, visible temperature and lubricant indicators for translating the temperature of the engine and the condition of its lubricating system during operation, an electrically operated and controlled circuit breaker for the circuit of the ignition system, said last named circuit breaking means of the ignition circuit having a separate normally open operating circuit and circuit closing means correlated with and operated by said temperature and lubricant indicators for closing the circuit upon the occurrence of a predetermined abnormal degree of temperature and/or condition of the lubricating system during operation of the 50 engine, and an additional circuit closure in the operating circuit of the circuit breaking means of the ignition circuit normally open when the engine is not operating but being automatically closed with delayed action by operation of the 55 engine.

3. In a protective system for operating internal combustion engines, a regular ignition circuit for the engine including a manually operable switch for opening and closing the circuit,

- 5 at will, a solenoid having a connection with said switch for automatically actuating it to break the ignition circuit, the operating and controlling circuit for the solenoid being normally broken and including a circuit closure correlated with and operated by an operating condition indicator for the engine whereby to close the circuit upon the occurrence of a predetermined abnormal condition, a supplemental circuit closure for said solenoid circuit normally open when the engine is not operating, and means for automatically closing said last-named circuit closure when the engine is operated, said means comprising a vacuum device operably connected to said circuit closure and having a communicable suction connection with the intake manifold of the engine.
- 10 4. In a protective system for operating internal combustion engines, a regular ignition circuit for the engine including a manually operable switch for opening and closing the circuit, at will, a solenoid having a connection with said switch for automatically actuating it to break the ignition circuit, the operating and controlling circuit for the solenoid being normally broken and including a circuit closure correlated with and operated by an operating condition indicator for the engine whereby to close the circuit upon the occurrence of a predetermined abnormal condition, a supplemental circuit closure for said solenoid circuit normally open when the engine is not operating, and means for auto-
- 15 20 25 30

matically closing said last-named circuit closure when the engine is operated, said means comprising a vacuum device operably connected to said circuit closure and having a communicable suction connection with the intake manifold of the engine, said vacuum device having provision for delaying its effective operation in closing said circuit breaker at the beginning of operation of the engine.

5. Automatic protective means for internal combustion engines comprising, in combination with the electrical circuit of a regular ignition system for operating the engine, an electrically operated circuit breaking switch for the ignition circuit having an operating circuit separate from the ignition circuit proper, a circuit breaker in the operating circuit for said switch of the ignition circuit proper, delayed action operating means actuated by the operation of the engine for closing said circuit breaker in the operating circuit of said switch of the ignition circuit proper, and an operating condition indicator for the engine provided with normally open circuit closing means in the operating circuit of said switch of the ignition circuit proper, said circuit closing means of the condition indicator operating to automatically close the operating circuit of said switch upon the occurrence of a predetermined abnormal operating condition of the engine translated through said indicator.

ROY W. JONES.
